UNITED STATES PATENT OFFICE.

ROMAN V. ZELEWSKI AND HERMANN SIEGEL, OF ENGIS, BELGIUM.

DEVICE FOR PUSHING BACK ORES INTO THE INTERIOR OF MECHANICAL MUFFLE ROASTING-FURNACES.

1,339,252.

Specification of Letters Patent.

Patented May 4, 1920.

Application filed July 20, 1917. Serial No. 181,931.

To all whom it may concern:

Be it known that we, ROMAN V. ZELEWSKI, a subject of the King of Prussia, residing at Engis, Villa d'Ehein, in the Kingdom 5 of Belgium, and HERMANN SIEGEL, a subject of the King of Prussia, residing at Engis, Grande Route, in the Kingdom of Belgium, have invented certain new and useful Improvements in Devices for Pushing Back 10 Ores into the Interior of Mechanical Muffle Roasting-Furnaces; and we do hereby declare the following to be a full, clear, and exact description of the invention, such as will enable others skilled in the art to 15 which it appertains to make and use the same.

Roasting ores by means of mechanical devices in muffle-roasting-furnaces such as the hand-roasting-furnaces nowadays in use 20 has hitherto been connected with difficulties in so far as at the ends of the reciprocating mechanical device for stirring up the ores, heaps of ores accumulated which did not get into the interior of the furnace but got 25 cool at the places of accumulation.

These cold ores were therefore not roasted sufficiently and eventually became a hindrance to the stirring devices when the heaps had became too high. Besides, they got 30 mixed with the ores which had already been well roasted, and thus spoiled the latter by mixing them again with unroasted sulfur.

The present invention has for its object 35 to avoid the afore-mentioned disadvantages and difficulties. It relates to a device by means of which mechanical muffle-roasting-furnaces, such as the hand-roasting-furnaces of Maletra - Hasenklever, Liebig - Eichhorn 40 and similar roasting-furnaces, are made usable for practice.

Another object is to make all mechanical parts easily accessible and allow them to get always rapidly cooled in their starting 45 position.

By means of the new device any accumulated heaps of ores can at necessity or regularly be pushed back into the interior of the furnace.

50 The invention is illustrated by way of example in the accompanying drawings, in which:

Figure 1 is a plan view of the device, Figs. 2 and 3 are side views (partly in

section) of the device with parts in different 55 positions.

Referring now to the drawings, in which like numerals of reference denote the same parts throughout all views, it will be noted that the new device is illustrated as applied to a stirrer 1 of any well-known construction. 2 are the drawing-bars by means of which the stirrer can be moved to and fro in the furnace across the ores for stirring up the latter. At a certain distance 65 behind the stirrer 1, the bars 2 are connected with each other by a cross-bar 3. The cross-bar 3 is attached to the drawing-bars 2 by means of bearing-like members 4. These members are provided at their 70 inner sides with vertical recesses 5 constituting sockets in which an elongated comb-like plate 6 is mounted. The plate is provided at its ends with pivots 7 which are received by the said recesses 5, these 75 recesses being of such dimensions that the pivots have enough play upwardly and laterally for allowing a free movement of the comb-like plate. The upper portion of the plate 6 is thickened on its entire length 80 as at 8 (Figs. 2 and 3). This portion tends, by its weight, to turn the plate 6 in one direction or the other. On the side facing the cross-bar 3 the said portion is provided with a projection 9 which can engage the 85 cross-bar, so that the comb will be held in the inclined position A shown in Fig. 2; in this position the plate will reach nearly to the bottom of the furnace.

When the stirrer is moved into the 90 interior of the furnace and the plate 6 is in the position A (Fig. 2) it will push the ores into the inner room of the furnace, where they are submitted to a good roasting effect. When the stirrer is withdrawn, the 95 plate 6 will engage the bottom of the furnace and thereby will be automatically tilted at once into the position B (Fig. 3). In this position the comb will, on its way back, pass across the ores without coming into contact 100 with the same, and as soon as it comes into its starting position it will again be brought into position A by some suitable stop 50, adapted to be positioned to engage the lug 9, on the comb 6. If the device is in the position A it can again be moved forward for pushing new heaps of ores into the furnace. The said stop is so constructed that it can 105

also be put into inoperative position, so that when the stirrer is reciprocated across the ores, the comb 6 will remain in position B and glide over the ores without affecting the same. Only in case of necessity, *i. e.* as soon as the ores have accumulated to a sufficiently high heap, is the stop again brought into operative position, so that the comb will operate in position A in the manner described.

10 While the device is shown in connection with a stirrer, it will be evident that it can also be constructed as an independent device which can be used in the same way and will have the same effect as that described 15 and illustrated.

It will further be evident that we do not wish to restrict ourselves to the form described and shown and that many changes can be made in the construction of the device without departing from the spirit of 20 our invention.

What we claim as new and desire to secure by Letters Patent is:—

1. In an apparatus of the class described, 25 the combination of a furnace, a frame mounted in the furnace to reciprocate, a plurality of fixed stirring devices depending from the inner end of the frame, a bar having trunnions and extending across the 30 frame, bearings formed in the frame to receive the trunnions, a comb depending from the bar, the trunnions being disposed near the bottom of the bar, the weight of the bar above the trunnions causing said bar and 35 the comb to tilt by gravity beyond a medial line, and means on the frame to limit the rocking movement of the comb and bar in either direction of movement of the frame.

2. In an apparatus of the class described, 40 the combination of a frame, stirring devices depending from the rear end of the frame, a comb pivotally supported in the frame and

weighted to tilt when past a vertical position, means for limiting the tilting of the comb, the comb being tilted by contact with 45 the fuel when the frame is withdrawn, and means for automatically reversely tilting the comb to operative position when the apparatus is withdrawn to normal position.

3. An apparatus of the class described, 50 comprising a pair of longitudinal side bars, a transverse bar connecting the side bars, a comb pivotally mounted in the side bars adjacent the transverse bar, and normally in an inclined position, the bottom of the comb 55 being positioned to engage the floor of a furnace when the apparatus is pushed inwardly, said comb being reversely tilted by the bottom engaging with the floor of the furnace when the apparatus is withdrawn, 60 and automatic means for resetting the comb at about the time the apparatus is in its initial position.

4. An apparatus of the class described, 65 comprising a frame formed with opposite aligned elongated bearings, a weighted bar having trunnions supported in the elongated bearings, a comb depending from the bar, the bottom of the comb adapted to rest upon the floor of a furnace, whereby when the apparatus is forced into a furnace, the comb will engage the material therein and move same, and when said apparatus is withdrawn the bottom of the comb engaging the floor of the furnace will cause the bar to 70 rock and its weight will position the comb above the material, and means for automatically resetting the comb to engage the material at about the time the apparatus reaches its initial position.

In testimony whereof we have signed our names to this specification.

ROMAN v. ZELEWSKI.
HERMANN SIEGEL.
